HOUSING FOR A PORTABLE SEWING MACHINE

Richard H. Arbib, New York, N. Y., assignor to White Sewing Machine Corporation, Lakewood, Ohio, a corporation of Delaware

Application August 26, 1957, Serial No. 47,504

Term of patent 14 years

(Cl. D70—1)

Fig. 2

Fig. 1 is a perspective view of a housing for a portable sewing machine embodying my new design and is taken looking from the front right hand corner of the machine.

Fig. 2 is a perspective view taken looking from the left hand rear corner of the machine.

I claim:

The ornamental design for a housing for a portable sewing machine, as shown.
